FIG. 7.

Attorney

UNITED STATES PATENT OFFICE

WILLIAM T. HORMES, OF CATONSVILLE, MARYLAND

SHELVING STRUCTURE

Application filed February 2, 1929. Serial No. 336,981.

This invention is a shelving structure primarily intended for use in stores and mercantile establishments generally, but not limited to such use.

5 One of the objects of the invention is to provide a simple and inexpensive form of shelving which may be readily erected or taken down at will, with an expenditure of a minimum of time and labor. A further object is to provide a shelving structure equipped with top and bottom sections, and interchangeable end sections for supporting the same, all capable of being economically produced. A further object is to provide 10 simple means for supporting the shelves or other storage units, and means by which the space between superposed shelves may be varied to suit different conditions. A further object is to provide a plurality of stacks of 15 shelving of the character mentioned and effective means for conveniently connecting the end frames of adjoining stacks. A further object is to provide a knockdown shelving structure which may be easily erected or 20 dismantled, and which will possess a maximum of rigidity and stability while in service.

The invention will be hereinafter fully set forth and particularly pointed out in the claims.

30 In the accompanying drawings:—
 Figure 1 is a front elevation illustrating two adjoining stacks of shelving constructed in accordance with the invention. Figure 2 is a view partly in section, illustrating one 35 of the stacks. Figure 3 is a horizontal sectional view taken on a line immediately above the base member. Figure 4 is a perspective view illustrating an assemblage of the shelf-supporting elements. Figure 5 is a similar 40 view illustrating a slight modification. Figure 6 is a perspective view illustrating another modification. Figure 7 is a detail perspective view illustrating the shelf-sustaining element of Figure 6. Figure 8 is a detail 45 sectional view of the joint between an end frame and a top section. Figure 9 is a similar view illustrating the corresponding joint with the base member. Figure 10 is a detail perspective view illustrating the pilaster. Figure 50 11 is a detail perspective view illustrating one

of the devices for connecting end frames of adjoining stacks. Figure 12 is a detail sectional view illustrating the means for retaining the pilaster in place.

Referring to the drawings, U designates a 55 knock-down unit container section consisting of a base member 10, a top member 11, and two end frames F. Each base and top member is constructed in a manner similar to the base and top members, respectively, commonly employed in standard type sectional unit structures, i. e. each of said sections comprises front and back walls a, joined by side walls b, and a top or shelf portion c. The top c of the base member serves as a shelf and the corresponding portion of the top member serves as the top of the stack. Secured to both of the side members b of the base member 10 are cleats 12, which are provided with longitudinal grooves or channels 13, and similar 60 cleats 14 are secured to both sides of the top member 11, except that the grooves or channels 15 are in the underside thereof. Engaging the grooves or channels 13 and 15 of the respective cleats 12 and 14 are tenon-like 65 projections 16, positioned at the respective top and bottom corners of the rectangular end frames F, each of which is of skeleton formation, i. e. constructed of longitudinally disposed stiles 17 connected by cross-pieces 18.

The stiles 17 are each provided with a longitudinal groove 21, to receive complementary longitudinal ribs 22, of the upright spacers 23 forming part of the shelf-supporting devices. Each upright 23 is placed in a vertical position with its lower end resting upon a cross piece 18, and its rib 22 in engagement with a groove 21, so as to be held against displacement in a position to support a shelf-sustaining element which may be of any desired construction. For instance, the shelf-sustaining element of Figures 4 and 5 consists of a cross piece 24, supported upon the upper ends of the spacers 23, so that the ends of the shelf S may rest thereupon. The cross bar may be provided with a rib 25 to engage with a complementary groove 26 formed in the underside of the shelf, as shown in Figure 5, or the tongue and groove structure may be omitted and the shelf anchored to the 70 75 80 85 90 95 100

cross bar 24 by means of a screw or other similar fastening, as shown in Figure 4. In either event, the cross bar 24 is provided with tenons 28 complementary to the grooves 21, so that lateral displacement thereof is prevented.

In the event that two or more stacks are to be arranged in a line, the frames F of adjoining stacks are connected by means of removable upright frame-locking members 29, 10 each of which is provided with two ribs 30 positioned to engage both grooves 21 of the respective abutted stiles 17 of the adjacent end frames of adjoining stacks. It is to be understood that while the cross pieces 24 are 15 employed, the locking members 29 are to be substituted for the spacer members 23.

In lieu of the spacer members 23 and the cross pieces 24, the frame-locking members may be arranged as indicated at 30^a, Figure 20 6, and the shelves supported by metal shelf-sustaining elements such as illustrated in Figures 6 and 7. Referring to said figures, it will be observed that the shelf sustaining 25 element consists of a metal bar or strip X, provided with offset shelf sustaining flanges X' and slots X² in their lower edges for the reception of suitably supported anchoring screws α^3 , which for purposes of illustration 30 are shown as mounted in the sides of the frame-locking member 30^a. It is obvious, however, that the strips α may be secured to the single width spacers 23 in precisely the same manner so as to function in identically 35 the same way. In either event the members α , while in position, aid the ribs of the upright members in preventing relative lateral movement of said members. The shelves are provided near their ends with transverse 40 grooves X⁴, to receive the upper edges the strips X, so as to lock the shelves against longitudinal movement.

In order to accommodate the pilasters P, the sides of the front vertical portions or 45 stiles of each frame F are cut away slightly to provide longitudinal recesses, as indicated at 31. One frame F of each stack is also provided with studs 32 projecting laterally from the front stile and located in the cut away 50 area 31, so as to be conveniently engaged by hooks 33 on the pilaster. By means of this arrangement the pilaster is engaged with and supported by one stack only, and it is not necessary to connect it with both stacks as 55 is now the common practice.

In practice, the shelf supporting elements 23, 24 and 29 may be made up in quantities and conveniently stored until needed, the uprights 23 and 24 being made in different 60 lengths so as to provide various spacing of the superposed shelves, as may be desired. The shelves, the top and bottom sections, and the frames F may also be made up in accordance with standard measurements, and each 65 stored in a knock-down condition until re-

quired. When it is desired to erect one or more stacks of shelving, the requisite number of bottom and top sections 10 and 11, respectively, frames F, and shelf supporting elements are selected. In erecting a stack, a 70 bottom section 10 is first placed in position, and the two upright frames F of the stack are engaged with the cleats 13 of said bottom section, after which the top sections 11 are engaged with the frames F, thus completing the 75 skeleton structure. A set of shelf spacers 23 or 29, as the case may be, of the desired length are then engaged with the grooves 21 of the frames, their lower ends resting upon the lower cross pieces 18, after which the desired 80 form of shelf supports are placed in position upon the upper ends of said uprights, with their tenons in engagement with the grooves 21. The shelf S may then be placed in position on the supports, the ends of said shelf 85 being reduced in width so as to pass between the stiles of the frames F, the shelf being anchored to the members 24 by either of the methods already described. Thus longitudinal movement of the shelf is prevented and 90 the entire structure is greatly stiffened. After a shelf has been positioned a new set of shelf supporting members may be placed in position upon the said shelf and a second shelf superposed thereon. It is obvious that 95 this operation may be repeated until the desired number of shelves have been placed in the stack. If the shelf support X is used in lieu of the members 24, the part 29^a should be the full height of the space between 100 shelves instead of the short spacers 23 and cross pieces 24.

When two or more stacks of shelving are to be arranged in alignment, the frames F are connected by means of uprights 29, the 105 ribs of which enter the grooves 21 of contiguous frames, so that the two stacks are held against relative longitudinal movement. The pilaster P may be placed in position over the space between two stacks, or removed at 110 will without disturbing either stack, or without disturbing the relation of the stacks with respect to each other. All that is necessary in placing the pilaster is that it shall be held in a vertical position at a high enough elevation to permit the hooks 33 to pass over their complementary studs, and then push the pilaster downwardly so as to completely engage the hooks. The pilaster is disengaged by a reverse movement.

In connection with the manufacture of store shelving and similar structures it is exceedingly desirable that the various components be so designed that they will require a minimum of storage space. Another factor to be considered is that sectional units or elements other than mere shelving are of varying kinds and are assembled in various different combinations. Limitation of storage facilities dictates a policy of storing units 120

or elements of each kind together for the convenient filling of requisitions for the elements of any particular job. Therefore, a knock-down unit container adapted either for display and storage units or shelving which facilitates the convenient handling also conserves storage space, and aids the assembly of the desired combinations.

Constructing the pilaster elements so as to be detachable from the unit containers facilitates the interchange of said containers from one position to another without imposing the necessity of commencing at one end of a row of said containers and moving all of them to provide clearance, as is now customary with regard to structures in which the pilaster is rigidly attached to the unit container. It will be observed that the present invention meets all of the foregoing requirements. For instance, a very simple form of shelving structure is provided, which is capable of being quickly erected or dismantled at will. Being constructed of interchangeable parts which may be manufactured in quantities, it will be readily seen that the cost of production may be maintained at a low figure and the parts may be readily stored until required. It will be particularly observed that the arrangement by which the shelves are supported is such that as the structure is erected it becomes stabilized and rigid, thereby rendering it unnecessary to extensively use fastening devices such as nails, screws and the like.

It is to be understood that while the invention has been described in detail as applicable to store shelving, it is not limited to such use. In other words, enclosed sectional units or any other well known type of merchandise display storing or supporting means may be substituted for shelving without departing from the spirit of the invention. Therefore, wherever the terms "shelving structure" and "merchandise storing" means are employed in the specification and claims, said terms are to be understood as including open or closed shelving, enclosed or open sectional units, or any other means for supporting, storing or displaying merchandise, which means is capable of being supported by a unit container section U, equipped with shelf sustaining elements of the character hereinabove disclosed, or equivalent means.

Having thus explained the nature of the invention and described an operative manner of construction and using the same, although without attempting to set forth all of the forms in which it may be made, or all of the forms of its use, what is claimed is:-

1. In a shelving structure, a unit container comprising laterally spaced skeleton end frames, and a top member and a bottom member interposed between said frames, the end faces of the bottom member and the lower

ends of each end frame having complementary portions by which said end frames are each independently and removably supported by the bottom section and normally held against lateral movement with respect thereto, means for removably engaging the top member with the upper ends of said end frames, and shelving supported by said end frames in planes between said top and bottom members. 70

2. In a shelving structure, a unit container comprising laterally spaced skeleton end frames, and a top member and a bottom member interposed between them, means for supporting the end frames upon said bottom member, the end faces of the top member and the upper end of each end frame having complementary portions by which said end frames are each independently and removably engaged with the top member and normally held against lateral movement with respect thereto, and shelving supported by said end frames in planes between the top and bottom members. 80 85

3. In a shelving structure, a unit container comprising skeleton end frames of approximately rectangular shape, a top member and a bottom member interposed between said frames, grooved cleat members secured to the end faces of the respective top and bottom members, the upper and lower ends of said end frames having projections shaped to enter the grooves of said cleats, so that the whole unit container is supported by the bottom section, said end frames being otherwise disconnected. 90 95 100

4. A shelving structure comprising a unit container section consisting of a base member, a top member, and skeleton end frames maintaining said members in spaced relation, so that merchandise storing means may be interposed between them in spaced relation thereto said frames having upper and lower cross bars, shelf sustaining means supported on the lower cross bars of said frames, and a shelf mounted upon said sustaining means. 105 110

5. A shelving structure comprising a unit container section consisting of a base member, a top member, and skeleton end frames of approximately rectangular form maintaining said members in spaced relation, so that merchandise storing means may be interposed between them in spaced relation thereto shelf sustaining means resting on the lower cross bars of said frame, a shelf resting upon said shelf-sustaining means, additional shelf sustaining means supported by said shelf, and a second shelf supported by the last mentioned shelf supporting means. 115 120

6. In a shelving structure, a unit container comprising end frames of approximately rectangular form, a top member and a bottom member interposed between said frames, the end faces of said top and bottom members and the upper and lower ends of said end frames having separable complementary por- 125 130

tions by which they are normally maintained in assembled relation, the vertical portions of said end frames having longitudinally disposed grooves therein, shelf spacing means having complementary portions shaped to enter said grooves, and a shelf sustained by said spacing means.

7. A shelving structure comprising a unit container section consisting of a base member, a top member, and skeleton frames of approximately rectangular form maintaining said members in spaced relation, the vertical portions of said frames having longitudinally disposed grooves, uprights having longitudinal ribs complementary to said grooves, shelf-sustaining cross pieces supported by said uprights, and a shelf sustained by said cross pieces.

8. A shelving structure comprising a unit container section consisting of a base member, a top member, and skeleton frames of approximately rectangular form maintaining said members in spaced relation, the vertical portions of said frames having their inner edges provided with longitudinal grooves, uprights having longitudinal ribs complementary to said grooves, shelf sustaining cross pieces supported by said uprights and also having portions projecting into said grooves, and a shelf resting upon said cross pieces.

9. A shelving structure comprising a unit container formed of end frames of approximately rectangular form, a top member and a bottom member interposed between said frames, the end faces of said top and bottom members and the upper and lower ends of said frames having separable complementary portions by which they are normally maintained in assembled relation, upright shelf spacers engaging the vertical portions of said end frames, shelf supporting members sustained by said upright spacers and held against lateral displacement, a shelf resting upon said supporting members, and means for anchoring said shelf to said supporting members.

10. A shelving structure comprising a unit container consisting of a base member, a top member and skeleton end frames of approximately rectangular form maintaining said top and bottom members in spaced relation, upright members engaging the vertical portions of said end frames, said upright members and said vertical portions having complementary means preventing relative lateral displacement, metallic strips supported by said upright members and provided with offset shelf-sustaining flanges, and a shelf resting upon said flanges.

11. A shelving structure comprising a unit container section consisting of a base member, a top member, and skeleton frames of approximately rectangular form maintaining said members in spaced relation, the vertical members of said frames having longitudi-

nally disposed grooves therein, shelf spacing members extending across and concealing said grooves, and also having retaining portions complementary to said grooves, shelf sustaining members supported by said uprights, and shelving supported by said members.

12. A shelving structure comprising a plurality of unit container sections arranged in alignment with the end of one section abutting the contiguous end of an adjacent section, each section being provided with end frames, shelf spacing uprights carried by the respective frames, part of said uprights having complementary means to engage contiguous end frames of adjoining sections, and shelves supported by said uprights.

13. A shelving structure comprising a plurality of unit container sections arranged in alignment with the end of one section abutting the contiguous end of an adjacent section, each section being provided with end frames having longitudinal grooves therein, shelf spacing uprights having ribs complementary to said grooves, some of said uprights having two parallel ribs to respectively engage the grooves of the frames of adjacent stacks, and shelves supported by said uprights.

14. In a shelving structure, a unit container section comprising end frames of approximately rectangular form, a top member and a bottom member interposed between said frames, the end faces of said top and bottom members and the upper and lower ends of said frames having separable complementary portions by which they are normally maintained in assembled relation, one side of the front vertical member of each frame having a cut-away portion, lateral studs projecting from the last mentioned end frame within the space defined by said cut-away portion, and a pilaster having hooks positioned to removably engage said studs.

15. A shelving structure comprising a plurality of unit container sections each provided with an end frame of approximately rectangular form, said sections being arranged in alignment with an end frame of one section abutting against the contiguous end frame of an adjoining section, one side of the front vertical member of each abutted end frame having a cut-away portion, lateral studs projecting from the other abutted end frame into the cut-away area of the other end frame, and a pilaster having hooks positioned to removably engage said studs.

16. In a shelving structure, a unit container section consisting of a top, a base, and two skeleton end frames connecting said top and said base, merchandise storing means carried by said frames, a second unit container section similar to the first section and positioned with one end adjacent to an end of said first section, the opposite faces of the end frames of adjacent sections being in abutted relation,

- one of said sections having a pilaster detachably connected thereto and positioned to cover the joint between the sections, and means engaging the contiguous abutted portions of 5 said end frames independently of said pilaster for binding said sections together.
17. A shelving structure comprising a unit container section consisting of a top, a base and two end frames connecting said top and 10 said base, a second unit container similar to the first mentioned one and positioned with one end adjacent to an end of the first section, the opposite faces of the end frames of adjacent sections being in abutted relation, 15 merchandise storing elements, a pilaster detachably engaging one of said abutted end frames and positioned to cover the joint produced by the abutted relation of the end frames, and shelf spacer members for suspending said merchandise supporting elements and cooperating with said end frames 20 to bind the sections together.
18. In a shelving structure, a unit container consisting of a top, a base and two end frames detachably connecting said top and said base so as to produce a knock-down unit, merchandise storing means carried by said frames, a second unit container section similar to the first section and positioned with 25 one end frame adjacent to and in abutted relation with an end frame of the first section, one of said end frames having a pilaster detachably connected thereto and positioned to cover the joint produced by the abutted 30 relation of said end frames, and means engaging the abutted end frames independently of said pilaster for binding said sections together.
19. In a shelving structure, a unit container consisting of a top, a base, and two end frames detachably connecting said top and said base so as to produce a knock-down unit, merchandise storing means carried by said frames, a second unit container section 35 similar to the first section and positioned with one end adjacent to an end of the first section, one of said sections having a pilaster detachably connected thereto and positioned to cover the joint between the sections, and 40 shelf supporting means having portions engaging the adjacent end frames of the unit sections to bind said sections together, said binding means having no engagement with the pilaster.
- 55 20. A shelving structure comprising two unit containers each consisting of a top, a base, and two end frames detachably connecting said top and said base so as to produce a knock-down unit, said knock-down units being arranged end to end with the adjacent end frames in abutted relation, merchandise supporting elements carried by said frames, a pilaster detachably secured to the end frame of one of said abutted end frames and 60 positioned to cover the joint between the 65
- abutted end frames, and sustaining means for said merchandise supporting elements also cooperating with said frames to bind the unit containers together.
21. A shelving structure comprising a plurality of unit containers each consisting of a base member, a top member and skeleton end frames of approximately rectangular form maintaining said top and bottom members in spaced relation, upright members engaging the vertical portions of adjoining end frames of adjacent unit containers, said upright members and said vertical portions having complementary means preventing relative lateral displacement of said unit containers, and means for supporting shelves in vertically spaced relation along said end frames. 70
22. A shelving structure comprising a plurality of unit containers each provided with an end frame of approximately rectangular form, the vertical portions of said end frames each having a longitudinally disposed groove therein, said unit container sections being arranged in alignment with an end frame of one section abutting against the adjacent end frame of an adjoining section, an upright member having longitudinal ribs complementary to said grooves so as to normally prevent lateral separation of each abutted pair of end frames, and means for supporting shelves in vertically spaced relation along said end frames. 75
23. A shelving structure comprising a plurality of unit container sections each provided with end frames of approximately rectangular form, the vertical portions of said end frames each having a longitudinally disposed groove therein, said container sections being arranged in alignment with an end frame of one section abutting against the adjacent end frame of an adjoining section, metal shelf supporting strips spaced vertically along said end frames, shelves resting upon said strips and held against lateral movement with respect to said metal strips, and upright members having longitudinal ribs fitting in the grooves of each pair of adjacent end frames so as to lock the abutted end frames together. 80
